UNITED STATES PATENT OFFICE.

HENRY L. JOHNSTON, OF PALMETTO, GEORGIA.

OIL-CUP.

SPECIFICATION forming part of Letters Patent No. 294,134, dated February 26, 1884.

Application filed January 16, 1884. (No model.)

To all whom it may concern:

Be it known that I, H. L. JOHNSTON, a citizen of the United States, residing at Palmetto, in the county of Campbell and State of Georgia, have invented certain new and useful Improvements in Oil-Cups, of which the following is a specification, reference being had therein to the accompanying drawings.

My invention has relation to oil-cups or lubricators for all kinds of journal-bearings; and its object is to provide an oil-cup of this kind, whereby a given quantity of oil or similar fluid lubricant may in a very simple and effective manner be fed to the journal; and to this end the novelty consists in the construction of the device, as will be hereinafter more fully described, and particularly pointed out in the claim.

In the accompanying drawings the same letters of reference indicate the same parts of my invention.

Figure 1 is a sectional elevation of my improved oil-cup. Fig. 2 is a transverse central section through the upper part of the cup, showing the vent and its stopper; and Fig. 3 is a plan view of a vehicle-hub, showing the manner of securing the oil-cup between the spokes of the wheel when applied to that use.

A is the oil-cup proper or reservoir, and is provided with a screw-cap, a, for filling. The cup A is wedge-shaped in form, and its sides B B extend beyond the top C, so as to form ears or lugs c c, by means of which the cup may be secured by screws to the spokes of a carriage-wheel, as shown very clearly in Fig. 3.

D is a central tube, its upper end secured in the top C, and extending a short distance through the bottom of the cup.

E is a piston-rod, working in the tube D through the screw-plug F, and it is provided with a handle, G, for operating it. This handle G has a small angular arm, H, the free end of which forms a stopper, I, for the vent-hole K.

Upon the lower end of the piston-rod E is secured a piston, L, and above this is a second piston, N, the two being separated by the collar O.

Between the upper piston, N, and the screw-plug F is a spiral spring, P, which serves to force the piston-rod down to the full extent of its stroke. The tube D is provided

with two or more inlet-holes, s s, communicating with the interior of the reservoir A, and in the normal position of the device these 55 holes are closed by the piston L, which extends a short distance below them when the rod is down.

In practice, the device is properly secured in place, and the screw-cap a removed, to fill 60 the reservoir, which being done, the cap is returned to its place. The oil or lubricant is now confined in the reservoir, and if the handle G be raised, the holes s s are opened by the piston L passing above them, and the 65 oil in the reservoir flows through the holes s s into the lower portion of the tube D, and thence to the axle or journal at the same time the holes s s are opened. The vent K is also opened by the stopper I being attached to the 70 handle and raised with it. This permits a very free flow of the oil, and of course greatly facilitates the operation; and it will readily be seen that the cup is a very economical one, as there is no possibility of wasting any of the 75 oil, but, on the contrary, it is used up to the last drop.

In practice I have found cork to be an excellent material for the pistons; but of course soft wood, rubber, or similar substances will 80 answer the purpose equally well.

While I have shown the oil-cup attached to a carriage-wheel, I do not wish to confine myself in its use thereto, as it will be readily seen that it is applicable to all sorts of journal-bearings wherever stated quantities of oil 85 are needed.

Having thus fully described my invention, what I claim as new and useful, and desire to secure by Letters Patent of the United States, 90 is—

The wedge-shaped oil-cup A, having vent K, and provided with the central tube, D, having inlet-holes s s, and the piston-rod E, provided with piston L, spring P, handle G, 95 and stopper-arm H I, substantially as and for the purpose set forth.

In testimony whereof I affix my signature in presence of two witnesses.

HENRY L. JOHNSTON.
